UNITED STATES PATENT OFFICE.

GILBERT L. CROWELL, JR., OF ARLINGTON, NEW JERSEY, ASSIGNOR TO
DOMINICK & HAFF, OF NEW YORK, N. Y.

DESIGN FOR A SPOON, &c.

SPECIFICATION forming part of Design No. 21,700, dated July 12, 1892.

Application filed June 2, 1892. Serial No. 435,318. Term of patent 14 years.

To all whom it may concern:

Be it known that I, GILBERT L. CROWELL, Jr., a citizen of the United States, and a resident of Arlington, in the county of Hudson and State of New Jersey, have invented and produced a new, original, and useful Design for the Handles of Spoons and Similar Articles, of which the following is a description, reference being made to the accompanying drawing, which illustrates the design and is made a part of the following specification.

The drawing shows the design applied to one face of a spoon-handle; but the design may be applied to the handles of other articles.

The general outline of the handle of the spoon is of pandurate or fiddle-shape form, the upper and broadest end of the same recurving inwardly to the shank. The top of the upper end or crown of the handle bears

the representation A of a disk set in a scroll-work framing. 20

B is a border extending along the side edges of the handle. This border (commercially known as the "Gadrone" style) is usually composed of outwardly-curving flutes alternately concaved and convexed, as also alternately pointed and rounded at the margin or outline. The face C of the handle is from the inner line of the border slightly curved to the concave or convex form. 25

What is claimed as new is—

The design for handles of spoons and similar articles, substantially as herein shown and described.

GILBERT L. CROWELL, JR.
